UNITED STATES PATENT OFFICE

EDWIN L. VONDERSAAR, OF INDIANAPOLIS, INDIANA

GAME

Application filed August 6, 1928. Serial No. 297,703.

This invention relates to a game which is described in reference to the accompanying drawing, in which—

Fig. 1 is a top plan view of a playing board 5 embodying my invention; and

Fig. 2 is a top plan view of the playing pieces.

Referring first to Fig. 1, I lay out a board 10 with an outer square as defined by the 10 corner spots or stations *a*, *b*, *c*, and *d*. Midway on each side of this square I locate the spots *e*, *f*, *g*, and *h* and connect one to the other consecutively by lines to form the square accordingly with its sides at forty-five 15 degree angles with the first named square. At the middle point on each side of the square *efgh*, I fix the spots *i*, *j*, *k*, and *l*, and consecutively connect one to the other by lines to form the square *ijkl* with sides parallel to the 20 square *abcd*. Following the same scheme, I locate spots to define the squares *mnop* and *qrst*.

Lines *aj*, *bk*, *cl*, and *di* are drawn between the corresponding spots. The playing pieces 25 which may be discs or buttons, Fig. 2, may be sixteen or eighteen in number, here shown as eighteen, with half of them, one color, as the red buttons 11, and the other half another color, as the black buttons 12. The game is 30 played as follows:

There are two players and each player provides himself with the eight or nine buttons 35 of one color, and the other player takes a corresponding number of the other color. The player making the first move places a button 11 on any one of the spots *a* to *q*. The opposing player may place one of his buttons 40 12 on any other spot he so desires. It is the intention of each player to form a triangle as is defined by the lines between any three adjacent spots.

For example, a triangle may be formed by a player when he has his own buttons on the spots *dih* but not on the spots *d e h*, since 45 there is an intervening spot *i* between the spots *e* and *h*.

When a player succeeds in forming a triangle with his own buttons he informs his opponent of the fact and then removes a 50 button of the opponent from any spot he may

select but he may not break a triangle of the opponent as long as there is any other opponent's button on the board that is not a part of a complete triangle. In the event either player makes a triangle without noticing the fact or overlooks informing his opponent of having formed a triangle, such player forfeits the right to remove one of his opponent's buttons as above indicated.

If the move is made whereby a triangle is 55 formed and the player making the triangle does not notice the fact, the opponent by calling attention to the fact of the triangle being formed but not announced has the privilege of removing the last placed button of 60 the player before the opponent places his own button in position.

The game continues until all of the sixteen or eighteen buttons, as the case may be, are placed on the board. After which, the player 70 who first started the game moves one of his buttons to another spot connected by a line from the one that button then occupies provided the spot to which he elects to move is unoccupied. All such moves must be along a line to the next spot thereon but no further, as for example, a button on spot *p* could move to *q*, but not over *q* to *m*.

A player may move from one spot to another and in his next turn move back to the first spot from which he last moved provided his opponent has not already occupied that spot in his turn of play. Upon each turn to move, the player may move along a line any button he chooses to the next adjacent 85 unoccupied spot, and only one move at a time is allowed a player in his turn. The object of such moving is at all times to form a triangle to permit the removal thereby of one of the opponent's buttons.

After six of one player's buttons have been removed by the opponent, the player having only three buttons (where nine to a side are used) left on the board then has the privilege of picking up one of his buttons in his turn of play and placing it on any unoccupied spot on the board regardless of its location, as for example, having a button on the spot *m*, he could put it on the spot *b* if unoccupied and 95 he so desired.

In the event that it should develop that each player be reduced to three remaining buttons each, both players then have the same privilege of placing a button on any unoccupied spot regardless of its location in his successive turns of play, each player always striving to form a triangle with his own buttons or to prevent his opponent from forming a triangle. When a player is reduced to less than three buttons on the board, he loses the game as he is no longer able to form a triangle. During the play, if a player allows his buttons to become so placed that he is no longer able to move to an unoccupied spot, he is blocked, and thereby loses the game.

Supposing there are buttons belonging to one player on the spots *h c* and *l* forming one triangle *hcl*, then if the same player is able to move a button to the spot *g* he is credited with forming a second triangle *clg*, it being permitted that the buttons on spots *l* and *c* be used in common in the two triangles. The same rule applies at any other stations, it being permissible to have one or two buttons in one triangle as buttons in common in a second triangle.

I claim:

In a game, a board laid out to have an outer square; a second square turned forty-five degrees from the first square and having its corners on the sides of said first square; a third square turned forty-five degrees from the second square and having its corners on the sides of the second square; a fourth square turned forty-five degrees from the third square and having its corners on the sides of the third square; a fifth square turned forty-five degrees from the fourth square and having its corners on the sides of the fourth square, and a station at each corner of each square connected only by lines which define the squares, and a line drawn from each corner of the first square to and terminating at the respective nearest corner of the third square, said last mentioned lines being the only lines on said board which are not sides of one of said squares, all of said lines being lines of movement of buttons between the stations which the lines connect, and two sets of buttons adapted to be played between said stations.

In testimony whereof I affix my signature.
EDWIN L. VONDERSAAR.
